GILBERT CURRIE, OF FOREST HILLS, PENNSYLVANIA, ASSIGNOR TO WESTINGHOUSE ELECTRIC & MANUFACTURING COMPANY, A CORPORATION OF PENNSYLVANIA

SAFETY DEVICE FOR CIRCUITOUS ELEVATORS

Application filed January 30, 1931. Serial No. 512,290.

My invention relates to safety devices for circuitous elevators and relates particularly to safety devices applied to circuitous elevators having two or more endless chains supporting and moving a plurality of receptacles in an endless path, for the purpose of preventing relative movement of the endless chains.

As a solution to the problem of parking 10 automobiles in congested areas of large cities, circuitous elevators have been proposed. The term "circuitous elevator" is applied herein to a conveyor structure of any type in which a plurality of receptacles for supporting loads are movable in an endless path.

One type of circuitous elevator for storing 20 automobiles, which has been proposed, is described in detail in the copending application of Henry D. James and Gilbert Currie, Serial No. 512,291, filed Jan. 30, 1931 and assigned to Westinghouse Electric & Manufacturing Company, and my invention is 30 illustrated as applied thereto, although it should be understood that it may be readily applied to a circuitous elevator of any type or a conveyor or other device having a plurality of elements normally movable in synchronism, for the purpose of stopping all of the elements if undesirable relative movement occurs between them.

In circuitous elevators of the type described in the above-mentioned copending application of Henry D. James and Gilbert Currie, as well as other similar types where- 35 in a plurality of load receptacles are pivotally suspended from and between a pair of endless flexible members or chains which are disposed vertically in parallel spaced relation and simultaneously movable in simi- 40 lar paths to move the receptacles in an endless path, it is possible for an accident to occur which permits or causes the endless chains to move relatively. In the event of such occurrence, the load receptacles will be 45 distorted, or, at least, abnormally oriented, so that loads positioned thereon will be displaced and seriously injured.

Likewise, serious damage to the elevator 50 structure itself may occur in the event of relative movement of the endless chains. For

example, in the event that the sheaves or sprocket wheels supporting the endless chains at their lower ends are keyed to a common shaft, relative movement of the endless chains will cause a torsion of the shaft and a consequent injury to the elevator structure, thus rendering the elevator inoperative for an indefinite period and causing loss of income to the owner, as well as inconvenience and annoyance to the patrons.

In order to prevent such consequences, as the result of the relative movement of the endless chains of a circuit elevator, I have provided a means for preventing such movement.

It is an object of my invention, therefore, to stop the movement of two or more members, which are designed to move normally in synchronism upon relative movement thereof.

It is another object of my invention to prevent distortion and abnormal orientation of the receptacles of a circuitous elevator, adapted for the storage of automobiles, and thereby prevent injury to the automobiles.

Other objects of my invention will be apparent from the following description, when considered in connection with the accompanying drawings, wherein

Figure 1 is a diagrammatic view, in side elevation, of a circuitous elevator adapted for the storage of automobiles to which my invention is applied.

Fig. 2 is a front view of an automobile storage structure, a portion being broken away to show the application of my invention to the circuitous elevator represented in Fig. 1.

Fig. 3 is an enlarged view, in side elevation, of a sheave or sprocket wheel for supporting an endless chain of a circuitous elevator and the method of attaching one of the commutators, comprising my invention, thereto.

Fig. 4 is a sectional view, taken on line IV-IV of Fig. 3, showing the method of establishing an electrical connection to a commutator attached to a sprocket wheel.

Fig. 5 is an enlarged view, in front elevation, of a contact finger or brush holder

which I employ to establish an electrical connection to a commutator.

Fig. 6 is a side view of the brush holder shown in Fig. 5.

5 Fig. 7 is a view corresponding to that of Fig. 5 but having the contact fingers removed and showing the slots for effecting adjustment of the position of the contact fingers.

10 Fig. 8 is a simplified control diagram illustrating, in part, the method of connecting the contact fingers engaging the commutators in a control circuit for the motor employed to drive the circuitous elevator.

15 Referring to Fig. 1, the circuitous elevator, to which my invention is herein specifically applied, comprises a building structure 11 constructed in a usual manner and having a plurality of slings, cages or receptacles 12 20 pivotally suspended at regular intervals from and between a pair of endless chains 13 and 14, disposed vertically in parallel spaced relation, and movable therewith in an endless path within the structure 11.

25 The endless chains are supported, in vertically displaced relation, by suitable sheaves or sprocket wheels 15 at top and bottom. Each of the sheaves 15 is keyed to a stub shaft 16 which is supported at the ends thereof on opposite sides of the sheave by suitable bearing members 17 suspended from, or otherwise suitably attached to, horizontally disposed structural members 18 which are attached, as by welding, to channel bars 19

30 disposed around the vertically extending portions of the endless chains to maintain them in a fixed path of movement. The channel bars 19 are supported upon a pedestal comprising four structural columns 20, disposed 35 at the corners of the building structure 11, and a pair of horizontally disposed structural members 21 each supported by two columns in parallel relation.

40 The two spaced members 21 are disposed parallel to the front of the building structure 11, and a horizontally-disposed structural member 22 is supported, at its ends, by the members 21, in such position that the receptacles 12 may pass freely thereby. The 45 channel bars 19 are supported upon the member 22 by means of horizontally disposed structural members 23 which are rigidly attached to the channel bars associated with adjacent vertically-extending portions of the 50 same endless chain.

55 The upper portions of the channel bars 19 are maintained in fixed spaced relation, in a manner similar to that described above, by means of structural members 24 and 25.

60 Vertically-extending structural members 26 are provided for supporting the upper end of the supporting structure of the endless chains to prevent lateral movement thereof with respect to the building structure 11. 65 The members 26 are slidably secured to the

building structure to permit upward movement of the chain-supporting structure caused by expansion resulting from temperature changes.

70 Each of the cages 12 is attached to the endless chains by means of pairs of angularly disposed bracket arms 27 which pivotally engage the ends of a receptacle. As indicated in Figs. 1 and 2, one pair of bracket arms 27 engages a trunnion disposed adjacent to the bottom edge of one end of a receptacle, and a second pair engages a trunnion disposed adjacent to the upper edge of the receptacle at the opposite end thereof. A construction of this character minimizes objectionable swaying and swinging of the receptacles 12 during movement in the endless path.

75 Any suitable means may be provided for moving the receptacles simultaneously. For purposes of illustration, I have provided a motor 28, supported upon a platform attached to the channel bars 19, for driving a pair of sprocket wheels 29 and 30 which engage the adjacent vertically-extending portions of the endless chains 13 and 14, respectively. The sprocket wheels 29 and 30 are keyed or splined to a common shaft 31 to which a gear wheel 32 is also keyed. The motor 28 drives the gear wheel 32 through a speed-reducing gear mechanism 33.

80 A doorway 34, (Fig. 1) having suitable doors, is provided at the ground floor level 35 for permitting the entrance and exit of automobiles to and from the receptacles 12.

85 The particular structure of the sling or receptacle is immaterial to my present invention, since any suitable support for automobiles may be provided. The structure of the receptacles shown herein is described, however, in detail in the co-pending application of Henry D. James and Gilbert Currie, above mentioned.

90 Referring to Figs. 3, 4 and 8, my present invention comprises a pair of commutators or commutating rings 36 and 36' which are movable synchronously at the same speed, with the movement of the endless chains 13 and 14, respectively. Any suitable drive connection may be provided for effecting the movement of the commutators 36 and 36'. For purposes of illustration, I have shown the commutator 36 suitably attached, as by screws 37, to one of the sheaves or sprocket wheels 15, which engages the endless chain 13. The commutator 36' is similarly attached to a sprocket wheel 15 which engages the endless chain 14. I have shown, in Fig. 3, the commutator 36 only and have shown it as applied to a lower sprocket wheel 15, but it should be understood that the commutators may be applied to sprocket wheels disposed at any desired location.

95 The commutators 36 and 36' are preferably of disc-shape disposed coaxially with re-

spect to their associated sprocket wheels. The commutators may, however, be cylindrical and suitably secured to the sprocket wheels in any desired manner. As illustrated, each 5 commutator comprises an insulating base 36a having a plurality of conducting segments 38 and insulating segments 39 radially disposed in alternate relation in an annular groove in the insulating base; the width of 10 the conducting segments being slightly greater than that of the insulating segments for a reason which will be hereinafter explained. It is desirable that the width or arcuate surface of a segment shall be as small as practicable, to thereby permit the provision of a 15 substantial number of segments, in order to obtain an immediate response to relative movement of the endless chains, as will be more clearly explained hereinafter.

20 A pair of insulating L-brackets 40 and 41, provided with spaced contact fingers 42 and 43, are disposed, preferably, on diametrically opposite sides of each of the commutators 36 and 36'. The brackets may be suitably 25 supported by the structural member 18, in such position that the contact fingers 42 and 43 engage the segments of the commutators associated therewith.

Referring more specifically to Figs. 5, 6 30 and 7, the brackets 40 and 41 are provided with spaced slots 44 for permitting the adjustment of the contact fingers 42 and 43 with respect to the commutators. Suitable bolts 45 and 46, one of which may serve as an 35 electrical terminal, extend through apertures in the contact fingers and, through the slot 44, to secure the fingers to the brackets 40 and 41.

The contact fingers of the bracket 40 are 40 properly so adjusted in their slots that, except for a short interval in transferring from conducting to insulating segments or vice versa, they both simultaneously engage an insulating segment 39 or a conducting segment 45 38 at the time the contact fingers of the bracket 41, likewise properly adjusted, simultaneously engage a conducting segment 38 or an insulating segment 39.

The conducting segments 38 on the commutators are made preferably slightly wider 50 than the insulating segments 39, in order to insure that, at a certain instant during the disengagement of contact fingers from, and the engagement of contact fingers with, conducting or insulating segments, both pairs of contact fingers on brackets 40 and 41 shall simultaneously engage conducting segments.

55 It is understood that, if contact fingers having considerable contact area are employed, the segments 38 and 39 may be equal in width, because one pair of contact fingers will engage a conducting segment prior to 60 the disengagement of a conducting segment

by the other pair of contact fingers associated with the same commutator.

However, where contact fingers have a "line-contact" area, it is exceedingly difficult to so adjust the position thereof that, for either direction of rotation of the commutators, simultaneous contact of the pair of contact fingers with different conducting segments may be effected. In order, therefore, to insure that, for both directions of rotation, this simultaneous engagement of the contact fingers with conducting segments of the same commutator shall occur, the conducting segments 38 on the commutators are made slightly wider than the insulating segments. The required difference in width between the conducting and the insulating segments is very slight.

Although the brackets 40 and 41 are illustrated as being on diametrically opposite sides of a commutator, it should be understood that any other angular relation thereof, which effects the same result, is permissible.

Referring to Fig. 8, a method is shown for connecting the contact fingers associated with both of the commutators 36 and 36', so that an electrical circuit is maintained alternately first through the contact fingers on brackets 41 and conducting segments of the commutators and then through the contact members on brackets 40 and conducting segments of the commutators; there being a short transfer interval during which all of the contact fingers are in engagement with conducting segments.

By means of a connection such as described, an electrical circuit is maintained through the contact fingers and the commutators as long as the endless chains 13 and 14 move synchronously and at the same speed. If a slight relative movement of the endless chains 13 and 14 occurs, the circuit through the contact fingers and the commutators is interrupted. My invention is, in effect, therefore, a switch which is normally closed but which opens in response to a slight relative movement of the endless chains 13 and 14 to effect the stopping of the movement thereof.

I have not shown, in detail, a motor-control circuit in Fig. 8, since it is deemed unnecessary. My invention constitutes a switch and it is readily connected in any circuit for controlling the actuation of a motor; for example, in a circuit for energizing the coils of direction relays.

The operation of my invention is best understood by an assumed operation. Let it be assumed that the commutators 36 and 36', in Fig. 8, are rotating synchronously, at the same speed, in accordance with the movement of the endless chains 13 and 14, respectively. At a particular instant, under the conditions assumed, the commutators 36

and 36' occupy relative positions, as shown in Fig. 8, in which the fingers 42 and 43 engage the central portions of conducting and insulating segments of the commutators. 5 At this particular instant, a circuit is established for permitting the motor 28 to be energized, which circuit extends from supply conductor L1, through conductors 50 and 51, contact finger 43b, a conducting segment 38b 10 of commutator 36', contact finger 42b, conductors 52, 53 and 54, contact finger 42a, a conducting segment 38a of commutator 36, contact finger 43a and conductors 55 and 56, to the motor-control circuit and thence to 15 supply conductor L2 (not shown).

Let it be assumed that the endless chains 13 and 14 continue to move simultaneously at the same speed, and that the commutators 36 and 36' are moved respectively in accordance with the movement thereof through a distance corresponding to the width of a conducting segment 38. It will be clear that, during the transfer of contact fingers from conducting to insulating segments or vice 20 versa, the contact fingers 42 and 43 of the brackets 40 engage a conducting segment 38 slightly before the disengagement of a conducting segment 38 by the contact fingers 42 and 43 on the brackets 41. After the commutators have rotated through a distance corresponding to the width of a segment 38, the contact fingers 42a and 43a in Fig. 8 are in simultaneous engagement with an insulating segment 39a, and the contact fingers 42b 25 and 43b are in simultaneous engagement with an insulating segment 39b. The circuit previously traced has, therefore, been interrupted, but another circuit was established through contact members 42c, 43c, 42d and 40 43d prior to the interruption of the circuit previously traced; the two circuits being in parallel. The circuit now extends from supply conductor L1, through conductors 50 and 51, contact fingers 42c, a conducting 45 segment 38a on commutator 36, contact finger 43c, conductors 52, 53 and 54, contact finger 43d, a conducting segment 38b on commutator 36', contact finger 42d and conductors 55 and 56, to the supply conductor L2, as previously 50 described.

Now let it be assumed that relative movement of the chains 13 and 14 occurs. In such case, a slight movement of the commutators 36 and 36' out of their relative positions, 55 shown in Fig. 8, effects the interruption of the circuits previously traced. If it be assumed that the commutator 36' moves relatively to the commutator 36, so that the contact fingers 42b and 43b engage an insulating segment 39b of the commutator 36' at the same time that the contact fingers 42a and 43a engage a conducting segment 38a of the commutator 36, the circuit previously traced therethrough is opened, and de- 60 energization of the driving motor is effected. 65

Likewise, if it be assumed that, upon small relative movement of the endless chains 13 and 14, the commutators 36 and 36' assume, at a particular instant, such relative positions that the contact fingers 42c and 43c 70 are in engagement with a conducting segment 38a of the commutator 36 at the same time the contact fingers 42b and 43b are in engagement with an insulating segment 39b of the commutator 36', the circuit previously 75 traced therethrough is interrupted and the deenergization of the motor 28 is effected.

Although I have shown only two commutators movable in accordance with the movement of two normally synchronously movable elements, it will be understood that more than two commutators may be employed, one for each of a plurality of normally synchronously movable elements, together with contact fingers associated with all of the commutators and connected together in such manner that, whenever relative movement between any of the movable elements occurs, the movement of all of them is stopped. It will be further understood that my invention is applicable to devices other than circuitous elevators or conveyors, in that it is applicable to any device or mechanism having a plurality of normally synchronously movable elements which must move in synchronism or not at all. 90

It will, therefore, be seen that I have provided a device for stopping the movement of two or more members, normally movable in synchronism, whenever relative movement 100 between the members occurs. It will be seen, further, that I have provided a means for preventing serious injury to a circuitous elevator and to automobiles stored therein, should relative movement of the conveyor 105 members thereof occur.

It is understood that my invention is capable of various modifications without a departure from the spirit thereof. I desire, therefore, that only such limitations shall be 110 imposed thereon as are necessitated by the prior art and the scope of the appended claims.

I claim as my invention:

1. In a safety device for a conveyor including a plurality of endless flexible members movable in similar endless paths, and motive means for moving said endless members, means responsive to relative movement of the endless members for stopping the movement thereof, said responsive means comprising a commutator for each of said endless members movable in accordance with the movement thereof, said commutators being constituted by a plurality of alternately spaced conducting and insulating segments, and two pairs of stationarily disposed contact fingers for each of said commutators, one pair being disposed to be connected by simultaneously engaging a conducting segment, while the 115

120

125

130

other pair are separated by their simultaneous engagement with an insulating segment, said contact fingers being connected to maintain a closed circuit, whereby said motive means may be energized from a source of energy supply when said endless flexible members move simultaneously at the same speed and to disconnect said motive means from the source of supply when said endless members move with respect to each other.

2. In a safety device for conveyors comprising a plurality of conveyor elements normally movable simultaneously at the same speed, means for stopping said conveyor elements upon relative movement thereof, said means including a commutator for each conveyor element movable in accordance with the movement thereof, each commutator having a plurality of alternately disposed conducting and insulating segments, and a plurality of contact members disposed in engagement with said commutator segments and adapted to maintain an electrical circuit closed while said conveyor elements move simultaneously at the same speed and to interrupt the circuit when the conveyor elements move relatively.

3. In a conveyor, a plurality of conveyor elements movable simultaneously at the same speed, and means for stopping said conveyor elements upon relative movement thereof, said means comprising a commutator for each conveyor element movable in accordance with the movement thereof, each commutator having a plurality of alternately disposed conducting and insulating segments, and a plurality of contact members for engaging said commutator segments and adapted to maintain an electrical circuit closed while said conveyor elements move simultaneously at the same speed and to interrupt the circuit when the conveyor elements move relatively.

4. In a conveyor, a plurality of conveyor elements movable simultaneously at the same speed, motive means for moving said conveyor elements, and means for stopping said motive means upon relative movement of the conveyor elements, said means comprising a commutator for each of said conveyor elements movable in accordance with the movement thereof, each commutator having a plurality of alternately disposed conducting and insulating segments, and a circuit for controlling said motive means including a plurality of contact members disposed in engagement with said commutator segments and adapted to maintain a circuit closed while said conveyor elements move simultaneously at the same speed and to interrupt the circuit when relative movement of the conveyor elements occurs.

In testimony whereof, I have hereunto subscribed my name this 22nd day of January 1931.
